UNITED STATES PATENT OFFICE.

LEWIS D. NELSON, OF UNION CITY, MICHIGAN, ASSIGNOR OF ONE-HALF TO R. M. NEALE, OF UNION CITY, MICHIGAN.

INTERNAL-COMBUSTION ENGINE.

1,366,018.

Specification of Letters Patent. Patented Jan. 18, 1921.

Application filed October 24, 1918. Serial No. 259,575.

To all whom it may concern:

Be it known that I, Lewis D. NELSON, a citizen of the United States, residing at Union City, in the county of Branch and State of Michigan, have invented certain new and useful Improvements in Internal-Combustion Engines, of which the following is a specification.

This invention relates to improvements in internal combustion engines.

The main objects of this invention are:

First, to provide in an internal combustion engine, an improved structure in which the exhaust and inlet manifolds are housed so that the inlet manifold is heated, the housing constituting an air heater for the carburetor.

Second, to provide a structure having these advantages adapted to be attached to an engine, such as the "Ford," without changing the same and without the necessity for drilling or tapping for the securing of the added parts.

Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing forming a part of this specification, in which:

Figure I is a detail side elevation of a structure embodying the features of my invention, the engine being shown conventionally.

Fig. II is a detail plan view of the structure shown in Fig. I.

Fig. III is an inverted view of my improved manifold housing.

Fig. IV is a detail vertical section through the manifolds and the housing on a line corresponding to line 4—4 of Figs. I, II and III.

In the drawing, similar reference characters refer to similar parts throughout the several views, and the sectional views are taken looking in the direction of the little arrows at the ends of the section lines.

Referring to the drawing, 1 represents the

body of an engine such as that employed in a "Ford" automobile, the same being shown in conventional form. 2 indicates the exhaust manifold and 4 the carburetor. The carburetor is provided with an air intake pipe 5 and is connected to the arm 6 of the intake manifold. The manifolds are secured by the clamping yokes 7 and the bolts 8, the manifolds and yokes being partially shown by dotted lines in Fig. I, the same being the usual yokes and bolts found on "Ford" automobile engines except that one of the bolts is removed and a longer bolt substituted therefor, as shown in Fig. IV, which bolt is employed as a securing means for the housing.

My improved housing comprises a front section or member 9 having bosses 10 and 11 for the manifold securing yokes and bolts, 70 the long bolt 8 being arranged through the boss 11 and provided with a clamping nut 12 for the housing. The front or main body section of the housing is provided with integral end walls. The top section 13 of the 75 housing is adjustably secured upon the front section 9, the top section being provided with projecting arms 14 on its front end having slots 15 therein to receive the bolts 16 whereby the top section may be adjusted to close the 80 top of the housing above the manifolds or to provide an opening to regulate the degree of heating as may be desirable in hot and cold weather. The bottom of the housing is closed by the rear section 17 which is disposed under and projects upwardly at the rear of the intake manifold 3, see Fig. IV, the same being removably secured to the front section by the bolts 18 disposed through opposed ears on the rear section and on the 90 front section, see Figs. I and III.

The front and rear sections have complementary extensions 19 and 20 respectively embracing the arm 6 of the intake manifold, and complementary sections 21 and 22 respectively providing an air intake pipe connection. A collar 23 is arranged on this air intake connection to slip over the end of the air intake pipe, the collar being secured by means of the set screw 24. The front section 100 of the housing is provided with an inlet opening 25, preferably disposed near the air

intake pipe connection, it being desired that the air passing to the air intake pipe should not be excessively heated. To further regulate the amount of heat passing through the air intake pipe it is provided with a damper like valve 26 which may be opened or partially opened to regulate the temperature of the air passing to the carburetor.

With this arrangement of parts the housing may be quickly applied and the parts are economical to manufacture and the structure is found highly efficient in use.

I have not in the accompanying drawing attempted to maintain the relative proportions of the various parts, that is, of the engine, carburetor, and manifolds, as the same vary in engines of different manufacturers.

Further, I have not attempted to illustrate various adaptations that are possible and contemplated by me as I believe the disclosure made will enable those skilled in the art to which my invention relates to embody or adapt the same as may be desired.

Having thus described my invention, what I claim as new and desire to secure by Letters Patent, is:

1. The combination with an engine body, intake and exhaust manifolds and securing yokes and bolts therefor, and a carburetor, of a housing comprising a front section disposed in front of said manifold and having bosses for said yokes and bolts, one of the bolts being disposed through said front section and provided with a nut, said front section being provided with integral end walls, a top section adjustably mounted on said front section to coact with the engine body to close the top of the housing or when raised to admit air thereto above the manifolds, and a rear section disposed below said manifolds and detachably secured to said front section to close the housing below said manifolds, said front and rear sections having complementary extensions for said intake manifold.

2. The combination with an engine body, intake and exhaust manifolds and securing yokes and bolts therefor, and a carburetor, of a housing comprising a front section disposed in front of said manifolds and having bosses for said yokes and bolts, one of the bolts being disposed through said front section and provided with a nut, said front section being provided with integral end walls, and a top section adjustably mounted on said front section to coact with the engine body to close the top of the housing or when raised to admit air thereto above the manifolds.

3. The combination with an engine body, intake and exhaust manifolds and securing yokes and bolts therefor, and a carburetor, of a housing comprising a front section dis-

posed in front of said manifold and having bosses for said yokes and bolts, one of the bolts being disposed through said front section and provided with a nut, said front section being provided with integral end walls, and a rear section disposed below said manifolds and detachably secured to said front section to close the housing below said manifolds, said front and rear sections having complementary extensions for said intake manifold.

4. The combination with an engine body, intake and exhaust manifolds and securing yokes and bolts therefor, and a carburetor provided with an air intake, of a housing comprising a front section disposed in front of said manifold and having bosses for said yokes and bolts, one of the bolts being disposed through said front section and provided with a nut, said front section being provided with integral end walls, a top section adjustably mounted on said front section to coact with the engine body to close the top of the housing or when raised to admit air thereto above the manifolds, and a rear section disposed below said manifolds, said front and rear sections having complementary extensions for said intake manifold, and to provide an air intake pipe connection, said front section having an air inlet opening therein adjacent said air intake connection.

5. The combination with an engine body, intake and exhaust manifolds and carburetor provided with an air intake pipe, of a housing comprising a front section disposed in front of said manifolds, a top section adjustably mounted on said front section to close the top of the housing or to admit air thereto above the manifold, and a rear section disposed below said manifold and detachably secured to said front section to close the housing below said manifold, said front and rear sections having complementary extensions for said intake manifold, and to provide an air intake pipe connection, said front section having an air inlet therein adjacent said air intake pipe connection.

6. The combination with an engine body, intake and exhaust manifold and carburetor, of a housing comprising a front section disposed in front of said manifolds, a top section adjustably mounted on said front section to close the top of the housing or to admit air thereto above the manifold, and a rear section disposed below said manifold and detachably secured to said front section to close the housing below said manifold, said front and rear sections having complementary extensions for said intake manifold.

7. The combination with an engine body, and intake and exhaust manifolds, of a housing comprising a front section disposed

in front of said manifolds and an adjustable top section adapted to be adjusted to close the top of the housing or to admit air thereto above the manifolds and means for conducting the heated air from the housing to point of use.

In witness whereof, I have hereunto set

my hand and seal in the presence of two witnesses.

LEWIS D. NELSON. [L. S.]
